UNITED STATES PATENT OFFICE.

WILLIAM SHRIVER AND WILLIAM M. PEARD, OF PHILADELPHIA, PENNSYLVANIA; SAID SHRIVER ASSIGNOR TO SAID PEARD.

INK-WELL.

SPECIFICATION forming part of Letters Patent No. 350,325, dated October 5, 1886.

Application filed February 27, 1886. Serial No. 193,429. (No model.)

To all whom it may concern:

Be it known that we, WILLIAM SHRIVER and WILLIAM M. PEARD, both citizens of the United States, residing in the city and county 5 of Philadelphia, State of Pennsylvania, have invented a new and useful Improvement in Ink-Wells, which improvement is fully set forth in the following specification and accompanying drawings, in which—

10 Figure 1 represents a vertical section of an ink-well embodying our invention. Fig. 2 represents a bottom plan view thereof. Fig. 3 represents a vertical section at a right angle to Fig. 1.

15 Similar letters of reference indicate corresponding parts in the several figures.

Our invention consists of an ink-well having its cover fitted in a desk or other support in such manner that it may be closed and 20 opened by sliding motions, its position being below the top of the desk or support, so as not to occupy said top, and when opened is comparatively concealed.

It further consists of a stop for limiting the 25 opening motion of the cover.

It further consists of a guard for protecting the lower part of the ink-well, the same having means for preventing displacement of the cover, the latter also serving to prevent dis- 30 placement of the well.

Referring to the drawings, A represents the top piece of a desk, or, in lieu thereof, that of an inkstand or other support for an ink-well, B, which is inserted in an opening, B', in the 35 piece A, and sustained by the flange on the shoulder C of said top. A portion of the bottom of the top piece, aside of the opening B', is recessed, and in the opposite walls thereof are grooves D, in which is fitted the cover E 40 of the ink-well, said grooves beginning at the under side of the piece A, extending in curved direction, and continuing into the walls of the opening B'.

F represents a guard for the portion of the 45 ink-well below the piece, the same being of the form of a tube which encircles the said portion of the ink-well, and depends from and is secured to the under side of the piece, said guard being constructed of metal or other 50 rigid material, and serving to protect the ink-

well from being struck by slates, &c., that may be placed in the desk, or otherwise injured from below.

On the under side of the cover E is a longitudinally-extending groove, G, into which projects a lug, H, which is cast with the guard F at one side of the upper end thereof. When the guard is omitted, the lug may be secured directly to the piece A. When the ink-well is located in the opening B', the cover is inserted in the grooves D and the guard F secured to the piece A, the lug H entering the groove G. The cover may be closed or moved over the ink-well, thus preventing the entrance of dust, &c., thereinto, and moved 60 back from the same, so that the ink-well is accessible. In the open position of the cover the upper or inner end of the groove G abuts against the lug H, thus providing a stop whereby the opening motion of the cover is 65 limited and displacement of the same prevented. A portion of the cover overhangs the flange or rim of the ink-well, so that the removal of the latter is prevented, and thus the cover and ink-well are retained in position. It will also be seen that the cover is 70 below the top of the desk, leaving said top unoccupied by the cover, and when the cover is opened it enters the body of the support in the recess at the side of the opening B', and 75 is thus comparatively concealed, and prevented from being broken, injured, or removed.

Having thus described our invention, what we claim as new, and desire to secure by Letters Patent, is—

1. An ink-well provided with a sliding cover, in combination with a frame or stand having within the same a recess adapted to receive the said cover and to conceal the same from view, substantially as described.

2. An ink-well with a sliding cover having grooves on the under face thereof, in combination with a support, A, having a recess and guides for the cover, and a guard with a lug, H, substantially as described.

3. An ink-well provided with a flange, a stand having a recess in the body of the same and an opening through which the ink-well is inserted, a shoulder on which said ink-well rests, and grooves in the stand, in which the 85 90 95 100

cover slides, a sliding cover with a groove on its under face, and a lug attached to the stand and operating in said groove, all substantially as described.

5. 4. An ink-well with a cover having a groove on the under face thereof, extending to near the ends, forming stops, a lug working in said groove, a guard for the ink-well, to which said

lug is attached, a stand having a recess, and the guides for the sliding cover, combined and operating substantially as described.

WM. SHRIVER.

WM. M. PEARD.
